United States Patent Office.

THOMAS GARRICK, OF PROVIDENCE, RHODE ISLAND.

Letters Patent No. 91,838, dated June 29, 1869.

IMPROVEMENT IN WRENCH.

The Schedule referred to in these Letters Patent and making part of the same.

To all whom it may concern:

Be it known that I, THOMAS GARRICK, of Providence, in the county of Providence, and State of Rhode Island, have invented an Improved Wrench; and do hereby declare that the following is a full and exact description, reference being had to the accompanying drawings, making a part of this specification.

The nature of my invention consists in a wrench, furnished with a self-adjusting jaw, whereby it is made to fit tapering or angular surfaces.

To enable those skilled in the art to make and use my invention, I will proceed to describe its construction and operation.

Figure 1 represents a side view, and

Figure 2, an edge view.

The movable jaw A turns upon the pin b, as a centre, against a curved recess or socket, c.

The pin d, moving in the curved slot e, holds the jaw A from moving laterally out of the socket c.

The flange f, upon the back part of the jaw A, en-

ters a curved groove in the socket, by means of which the jaw A is steadied, and prevented from cramping. If this flange is made dovetailing, entering a corresponding groove in the socket, the pin b may be dispensed with.

Any other suitable mode of fastening the self-adjusting jaw A to its socket may be adopted, and either or both jaws of a wrench may in like manner be made self-adjusting. By means of this free adjustment of the jaws, they may be caused to fit and take hold of any angular or inclined surfaces.

What I claim as my invention, and desire to secure by Letters Patent, is—

A swivel, or self-adjusting jaw, operating laterally in a curved socket, substantially as described.

THOMAS GARRICK.
